UNITED STATES PATENT OFFICE.

ASA L. DUDLEY AND JOHN J. SCHMIDT, OF GLENVILLE, NEBRASKA.

MANURE-SPREADER.

1,108,150.

Specification of Letters Patent. Patented Aug. 25, 1914.

Application filed March 28, 1914. Serial No. 828,010.

To all whom it may concern:

Be it known that we, ASA L. DUDLEY and JOHN J. SCHMIDT, citizens of the United States, residing at Glenville, in the county of Clay and State of Nebraska, have invented certain new and useful Improvements in Manure-Spreaders, of which the following is a specification, reference being had to the accompanying drawings.

10 This invention relates to an attachment for manure spreaders and similar machines and broadly stated, embodies certain improved mechanical features whereby such machines may be employed for the distribution or spreading of straw over the ground.

15 The invention has for its primary object to provide an attachment of the above character embodying a follower, and means for intermittently moving the follower to forcibly feed the straw to the cylinder of the spreader.

20 The invention has for another object to provide an attachment for manure spreaders which may be easily and quickly mounted in place upon the body of the spreader, said attachment including a follower for forcibly feeding the straw to the spreader cylinder, mechanism for imparting a slow intermittent feeding travel to the follower and 25 a comparatively rapid reverse or forward movement thereof, and means automatically actuated at the end of the forward and rear travel of the follower to render said mechanism inoperative.

30 35 The invention has for a further object to produce an attachment which may be applied to various forms of manure spreaders now in common use without necessitating material alterations therein, and which will 40 satisfactorily and efficiently perform the functions for which the same is devised, without injury to the parts of the spreader mechanism or in any way impairing its continued usefulness.

45 50 With the above and other objects in view, as will become apparent as the description proceeds, the invention consists in certain constructions, combinations and arrangements of the parts that we shall hereinafter fully describe and claim.

55 For a full understanding of the invention, reference is to be had to the following description and accompanying drawings, in which—

Figure 1 is a side elevation showing our

improved straw spreading attachment arranged upon a manure spreader; Fig. 2 is a longitudinal section thereof; Fig. 3 is a section taken on the line 3—3 of Fig. 1; Fig. 4 is an enlarged elevation illustrating the reverse arrangement of the drive gearing for the follower with respect to the arrangement shown in Fig. 1; Fig. 5 is a transverse section taken on the line 5—5 of Fig. 1; Fig. 6 is a section taken on the line 6—6 of Fig. 1. Fig. 7 is a detail section illustrating the trip device.

Referring in detail to the drawings, 5 designates the body of a manure spreader, which is mounted in any suitable manner at its front and rear ends upon the supporting wheels 6 and 7 respectively.

8 designates the spreading or distributing roller which is mounted in the rearwardly and upwardly inclined arms 9 fixed to the body of the spreader and is driven through the medium of a chain 10 from the rear wheel axle.

Our improved straw spreading attachment includes a suitable hopper or rack for the straw consisting of side walls 11 which have lower inwardly inclined portions 12 secured to opposite edges of a bottom or floor 13. To the side walls 11 a vertically disposed series of strap bars 14 are secured which are adapted to be received in spaced sleeves or cuffs 15 secured to the side walls of the spreader body 5. To the rear ends of the side walls 11 of the straw receiving rack or hopper, longitudinally extending rearwardly projecting bars 16 are secured. The comparatively short longitudinal bars 17 are also secured to the side walls 11 above the bars 16. Upon the inner sides of the walls 11, longitudinally extending rails or cleats 18 are provided for the support of a follower 19. This follower is longitudinally movable between the side walls of the hopper or straw rack to forcibly feed the straw to the distributing or spreading roller 8 in a manner which will be fully pointed out in the following description.

In suitable bearings mounted upon the upper edges of the rearwardly extending bars 16, the ends of a beater shaft 20 are journaled. This shaft is provided with a plurality of longitudinally extending blades 21 which are adapted to engage upon the straw and beat or force the same downwardly upon the teeth of the rotating

spreader cylinder 8. The rotating blades 21 are covered by means of the shield plate 21', said plate preventing the material being thrown upwardly and rearwardly by the blades in their rotation. Upon one end of the shaft 20, a sprocket wheel 22 is loosely mounted and is connected by an endless drive chain 23 with a similar sprocket wheel 24 carried by one of the rear supporting wheels 7. A clutch member 25 is keyed upon the beater shaft 20 for engagement with clutch teeth provided upon the sprocket wheel 22 whereby said wheel may be locked to the beater shaft. This sliding clutch member is actuated through the medium of a lever 26 fulcrumed upon the bar 17 and connected by the rod 27 to a lever 28 which is mounted upon one of the side walls 11 of the straw rack or hopper at its forward end. This lever is provided with the usual spring pressed dog for engagement with the teeth of a rack segment 29. An additional smaller sprocket wheel 30 is also fixed upon the end of the beater shaft 20 and is connected by 25 means of a sprocket chain 31 to a sprocket wheel 32 which is journaled upon a stub shaft 33 fixed in a vertically movable plate 34. One face of this sprocket wheel is provided with a gear 35 for engagement with a gear wheel 36 journalized upon the end of a stub shaft 37 which is suitably mounted upon one of the side walls 11. The plate 34 is provided with an elongated longitudinal slot 38 for the accommodation of this latter shaft. The upper and lower ends of this plate are also provided with slots 39 through which stud bolts 40, fixed in the side wall 11 of the hopper, project. The gear wheel 36 meshes with the teeth of a pinion 41 which is secured to or integrally formed with a sprocket wheel 42, said sprocket wheel being journaled upon a stub shaft 43 secured in the wall 11. This sprocket wheel is traversed by the chain 44 which extends around a similar sprocket wheel 45 fixed upon one end of a transverse shaft 46 journaled at its ends in supporting members 47 secured to the rearwardly extending bars 16.

48 indicates a tensioning pinion for the chain which is engaged with one stretch thereof.

Upon the shaft 46 adjacent its opposite ends, sprocket pinions 49 are fixed. These pinions are connected by means of the endless chains 50 to similar sprocket pinions 51 which are rotatably mounted upon the bracket arms 52 secured to the rear ends of the longitudinal rails or cleats 18.

The follower 19 above referred to is preferably in the form of a plurality of parallel bars 53 extending transversely between the side walls 11 and connected by a series of bars 54. The upper bar 53 at its ends is suitably secured to the upper stretches of the respective chains 50, so that the same is

moved by said chains between the side walls 11. The front ends of these side walls are connected by means of a transverse rod 55.

To the rear edge of the vertically movable plate 34, a rod 56 is rigidly secured, the ends of said rod being horizontally disposed and the intermediate portion thereof extending in parallel relation to the plate 34. A lever 57 is pivotally mounted intermediate of its ends as at 58 upon the vertical portion of the rod 56. In the lower end of this lever, one end of a dog or pawl 59 is fulcrumed, the other end thereof being disposed below the gear 36 and adapted for engagement with the teeth thereof. This dog is adapted to move vertically in a guide loop 60 which is secured upon the rod 56. The upper end of the lever 57 is pivotally connected to a pitman 61, the other end of said pitman being eccentrically connected to the sprocket wheel 32.

62 indicates a substantially U shaped bar, one arm of which is pivotally connected at its upper end as at 63 to the upper portion of the horizontal rod 56. The opposed arm of this U shaped lever is fulcrumed at its lower end as indicated at 64 upon the side wall 11 of the straw rack or hopper. The rear end of a longitudinally extending rod 65 is pivotally connected to the upper end of this latter arm of the lever 62 and is pivotally connected adjacent its forward end to a lever 66. The lower end of this lever is fulcrumed as at 67 upon the side wall 11 of the hopper and carries a spring pressed friction block for engagement with the upper edge of a curved bar 68. At the opposite ends of the rod 65, the same is provided with the trip fingers 69, which project through slots 69' in the side wall 11 and are disposed in the path of movement of the upper bar of the follower 19. To the upper horizontal portion of the bar 56, one end of a chain 70 is attached. To the lower end of this chain, a coil spring 71 is connected, said spring being secured to the pawl 59 intermediate of its ends, and serving to normally hold said pawl against the gear wheel 36 in the movement of the lever 57. The spreader is of course provided at its rear end with the usual rake 72 through the tines of which the straw is drawn by the teeth upon the rotating cylinder 8.

Having now fully described the construction and arrangement of the several parts of the invention, its operation will be understood as follows: Assuming that the rack or hopper has been supplied with straw, and the gear 33 disengaged from the gear 36 and the pawl 59 engaged with said latter gear by elevating the plate 34 by pulling the lever 66 forwardly; in the movement of the machine over the field, the sprocket wheel 32 is rotated through the medium of the power transmission chains 23 and 31

and the lever 57 oscillated upon its fulcrum by the pitman 61. Thus the pawl 59 is reciprocated longitudinally in the guide loop 60 against the action of the spring 71 and its forward end moved over the teeth of the gear 36, thus imparting an intermittent rotation to said gear. This gear is held against reverse turning movement by a spring pressed pawl 73 mounted upon the plate 34. The gear 36, meshing with the pinion 41 will rotate the sprocket wheel 42, which in turn through the medium of the chain 44 and sprocket wheel 43 rotates the rear transverse shaft 46, as indicated by the arrows in Fig. 1. In this manner, it will be seen that a step by step or intermittent longitudinal movement is imparted to the chains 50, the follower 19 of course being correspondingly moved from the front to the rear end of the rack or hopper containing the straw. The straw is thus forcibly fed to the beater blades 21 and by said blades directed to the rotating toothed cylinder 8, said cylinder drawing the straw between the tines of the rake 72 and spreading the same upon the ground as will be readily understood. When the follower 19 reaches the end of its rearward movement, the upper bar 53 thereof will engage the trip finger 69 on the rear end of the rod 65, and move said rod rearwardly to a sufficient extent to lower the plate and dispose the pawl 59 out of engagement with the teeth of the gear 36, the lever 66 being moved to a substantially central vertical position upon the curved bar 68. When it is desired to move the follower to the forward end of the straw hopper, the operator simply shifts the lever 66 rearwardly, thus forcing the plate 34 downwardly to a further extent and engaging the teeth of the gear 33 with the teeth of the gear 36. The gear 33 being rotated by the chain 31, it will be obvious that the direction of rotation of the gear 36 is reversed, and a continuous movement from the rear to the front end of the rack or hopper imparted to the follower by means of the mechanism above described. When the follower again reaches the forward end of its travel, it engages the trip finger on the forward end of the rod 65 and shifts said rod so as to return the lever 66 to its vertical position and render the operating mechanism inoperative. When the lever 66 is again shifted forwardly, it will be understood that the intermittent rearward movement of the follower is repeated to forcibly feed the straw to the distributing mechanism. From the foregoing description taken in connection with the accompanying drawings, the construction, manner of operation and several advantages of our invention will be clearly and fully understood. As the device consists of but comparatively few parts,

it will be appreciated that the same is light in weight and may be readily lifted into position upon the body of the spreader.

The adoption of our improved straw spreading mechanism will require no material alterations in the construction of the spreader or prevent its subsequent use for spreading of manure or fertilizer. By the comparatively rapid continuous forward movement of the follower after the straw has been completely discharged from the rack or hopper, it will be apparent that it is only necessary for the machine to move forwardly a few feet. Thus but a comparatively restricted portion of the ground surface will be uncovered by straw, in the movement of the machine across a field. It will further be manifest that by means of our invention we have materially increased the utility of the ordinary manure spreader so that the same will satisfactorily perform two important purposes.

Our improved straw feeding and distributing mechanism being comparatively simple in its construction, may be produced at small manufacturing cost and is also highly durable as well as efficient in practical operation.

While we have shown and described the preferred construction and arrangement of the several elements, it is to be understood that the invention is susceptible of considerable modification therein and we therefore reserve the privilege of resorting to all such legitimate changes as may be fairly embodied within the spirit and scope of the invention as claimed.

Having thus described the invention, what is claimed is:

1. The combination with a manure spreader provided with a distributing cylinder, of a hopper adapted to be mounted upon the body of the spreader, endless chains mounted upon the side walls of the hopper, a follower secured to the upper stretches of said chains, and means for operating said chains to impart an intermittent rearward movement to the follower to forcibly feed the material to the distributing cylinder.

2. The combination with a manure spreader provided with a distributing cylinder, of a hopper adapted to be mounted upon the body of the spreader, endless chains mounted upon the side walls of the hopper, a follower secured to the upper stretches of said chains, means for operating said chains to impart an intermittent rearward movement to the follower to forcibly feed the material to the distributing cylinder, and a trip device actuated by the follower at the end of its rearward movement to render said chain operating means inoperative.

3. The combination with a manure

spreader provided with a distributing cylinder, of a hopper adapted to be mounted upon the body of the spreader, endless chains mounted upon the side walls of the hopper, a follower secured to the upper stretches of said chains, means for operating said chains to impart an intermittent rearward movement to the follower to forcibly feed the material to the distributing cylinder, a trip device actuated by the follower at the end of its rearward movement to render said chain operating means inoperative, and manually operable means to further actuate the trip device whereby the movement of the follower is reversed by said operating means.

4. The combination with a manure spreader provided with a distributing cylinder, of a hopper adapted to be mounted upon the body of the spreader, endless chains mounted upon the side walls of the hopper, a follower secured to the upper stretches of said chains, means for operating said chains to impart an intermittent rearward movement to the follower to forcibly feed the material to the distributing cylinder, a trip device actuated by the follower at the end of its rearward movement to render said chain operating means inoperative, and manually operable means to further actuate said trip device whereby the movement of the follower is reversed and an uninterrupted forward movement imparted thereto by the operating means.

5. The combination with a manure spreader provided with a distributing cylinder, of a hopper adapted to be removably mounted upon the body of the spreader, endless chains mounted upon the side walls of said hopper, a follower secured to the upper stretches of said chains, gearing for driving said chains including a power transmission gear, a shiftable driven gear adapted to engage said transmission gear, means actuated in the rotation of the driven gear to impart an intermittent rotary movement to the transmission gear in one direction, whereby the follower is intermittently moved rearwardly in the hopper to feed the material to the distributing roller, and manually operable means to shift said driven gear and said means whereby said means is disengaged from the transmission gear and the driven gear is engaged with the transmission gear and the direction of rotation of the latter reversed, to move the follower forwardly in the hopper.

6. The combination with a manure spreader provided with a distributing cylinder, of a hopper adapted to be removably mounted upon the body of the spreader, endless chains mounted upon the side walls of said hopper, a follower secured to the upper stretches of said chains, gearing for driving said chains including a power transmission

gear, a shiftable driven gear adapted to engage said transmission gear, means actuated in the rotation of the driven gear to impart an intermittent rotary movement to the transmission gear in one direction, whereby the follower is intermittently moved rearwardly in the hopper to feed the material to the distributing roller, manually operable means to shift said driven gear and said means whereby the gear is engaged with the transmission gear and the direction of rotation of the latter reversed, to move the follower forwardly in the hopper, and means actuated by the follower at the end of its movement in each direction to shift said driven gear and the means actuated thereby and move the same out of coöoperative engagement with the transmission gear.

7. The combination with a manure spreader provided with a distributing cylinder, of a hopper adapted to be removably mounted upon the body of the spreader, endless chains mounted upon the side walls of said hopper, a follower secured to the upper stretches of said chains, gearing for driving said chains including a power transmission gear, a shiftable driven gear adapted to engage said transmission gear, means actuated in the rotation of the driven gear to impart an intermittent rotary movement to the transmission gear in one direction, whereby the follower is intermittently moved rearwardly in the hopper to feed the material to the distributing roller, manually operable means to shift said driven gear and said means whereby the gear is engaged with the transmission gear and the direction of rotation thereof reversed, to move the follower forwardly in the hopper, means actuated by the follower at the end of its movement in each direction to shift said driven gear and the means actuated thereby and move the same out of coöoperative engagement with the transmission gear, and manually operable means for further shifting said driven gear and said means to alternately engage the same with the transmission gear and reverse the movement of the follower.

8. The combination with a manure spreader provided with a distributing cylinder, of a hopper adapted to be removably mounted upon the body of the spreader, chains mounted upon the side walls of said hopper, a follower secured to the upper stretches of said chains, gearing driven from one of the wheel axles for operating said chains, said gearing including a transmission gear, a shiftable plate, a driven gear mounted upon said plate on one side of the transmission gear and adapted to engage the transmission gear, a pawl adapted to engage the transmission gear at the opposite side thereof, means actuated by the driven gear for reciprocating said pawl whereby an intermittent rotary movement is imparted to the

transmission gear to move the follower rearwardly and forcibly feed the material to the distributing cylinder, means actuated by the follower for shifting the plate in relatively 5 opposite directions at the end of its travel in opposite directions to disengage the gear and pawl from the transmission gear and stop the movement of the follower, and additional means for manually operating said 10 last named means and further shift said plate to engage the driven gear or the pawl with the transmission gear and reverse the movement of the follower.

9. The combination with a manure spreader 15 provided with a distributing cylinder, of a hopper adapted to be removably mounted upon the body of the spreader, endless chains mounted upon the side walls of the hopper, a follower secured to the upper 20 stretches of said chains, gearing driven from one of the wheel axles of the spreader for operating said chains, said gearing including a power transmission gear, a shiftable member, means mounted upon said member 25 for imparting an intermittent rotary movement to the transmission gear in one direction, and a continuous movement to said gear in the opposite direction, and manually operable means for actuating said shiftable 30 member to drive the transmission gear in either direction and reverse the movement of the follower.

10. The combination with a manure spreader provided with a distributing cylinder, of a hopper adapted to be removably 35

mounted upon the body of the spreader, endless chains mounted upon the side walls of said hopper, a follower secured to the upper stretches of said chains, gearing driven from the rear wheel axle of the spreader to operate 40 said chains, said gearing including a power transmission gear, a shiftable plate, a driven gear rotatably mounted upon said plate to engage the transmission gear on one side thereof, a spring held pawl to engage 45 the transmission gear on the opposite side, means actuated by the driven gear for reciprocating said pawl to impart an intermittent rotation in one direction to the transmission gear, a pivotally mounted lever connected to said shiftable plate to actuate the same, a manually operable lever mounted upon the forward end of the hopper, a rod connecting said levers, trip fingers on said rod adjacent its opposite ends adapted to be 50 engaged by the follower to shift said plate and disengage the driven gear or the pawl from the transmission gear, the operation of said latter lever further shifting said plate to engage the driven gear or the pawl with 55 said gear and reverse the movement of the follower.

In testimony whereof we hereunto affix our signatures in the presence of two witnesses.
